UNITED STATES PATENT OFFICE.

ARTHUR J. BROWN, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

CONTROLLER-OPERATING MEANS.

No. 854,688.

Specification of Letters Patent.

Patented May 21, 1907.

Application filed August 27, 1906. Serial No. 852,247.

To all whom it may concern:

Be it known that I, ARTHUR J. BROWN, a citizen of the United States, residing at Norwood, in the county of Hamilton and State of Ohio, have invented certain new and useful Improvements in Controller-Operating Means, of which the following is a full, clear, and exact specification.

My invention relates to means for operating motor-controllers, and its object is to render more positive and accurate the operation of a controller employing quick-break mechanism.

In motor-controllers in which heavy currents are handled and especially in railway controllers it is advisable to have the operating mechanism so constructed that a very rapid movement from one operative position to the next is obtained. This rapid movement provides a quick break between the contacts of the controller thereby minimizing the necessity for powerful blow-out magnets and other special devices for preventing the formation of arcs.

My present invention is an improvement on the invention set forth in Patent No. 815,578 issued March 20, 1906, to The Bullock Electric Manufacturing Company, a corporation of Ohio, on an application filed by me.

In one aspect my invention consists of the combination of a shaft, preferably the operating shaft of a controller, a notched member, a sliding bolt arranged to engage the notches of said notched member to lock the shaft in any desired position, a handle mounted upon the shaft and yieldingly connected thereto, and means for moving said bolt out of engagement with the notched member when the handle has been moved into the desired position to permit the shaft to rotate under the action of said yielding connection into a position corresponding to that into which the handle has been moved.

Other features of my invention will appear from the description and drawings and will be particularly pointed out in the claims.

Figure 1 is a front elevation of the upper part of a controller embodying my invention, some of the parts being shown in section on the line 1-1 of Fig. 2. Fig. 2 is a plan view of the controller of Fig. 1 with some of the parts broken away; and Fig. 3 is a view

somewhat similar to Fig. 2, but showing the relation of the parts when the controller is about to move from one position to another.

Referring to the drawings, the controller casing is represented by 4, the cap plate by 5 and the controller shaft by 6. Mounted from the upper end of said shaft 6 and keyed thereto is an arm 7, which carries a sliding bolt 8 having an enlarged head 9 integral therewith or otherwise firmly attached thereto. The bolt 8 is normally pressed outwardly by a spring 10 into engagement with the notches 11 of an internally notched ring 12. This ring 12 is supported from the cap plate 5, as by a plurality of pillars 13. The notches 11 of the notched ring 12 correspond to the operating positions of the controller. The "off" position is indicated by the notch 11^a, the operating mechanism being shown in that position in Fig. 2. The operating handle 14 is loosely mounted on the shaft 6 so that it can be rotated relatively thereto, but is prevented from movement longitudinally of the shaft as by the screw 15. Extending downwardly from the operating handle 14 are three pins 16, 17, and 18, while extending upwardly from the arm 7 are two pins 19 and 20. A spring 21 extends from the pin 16 to the shaft 6, being located between the pins 19 and 20.

When the handle 14 is moved from one position to the next, say in a forward or clockwise direction from notch 11^a, the spring 21 engages pin 19, and being stretched thereby, tends to draw the arm 7 with its associated controller mechanism after the handle 14. However actual rotation of the arm 7 is prevented by the engagement of the bolt 8 in the notch 11^a until the handle 14 has reached the next operative position, when by reason of the engagement between the pin 17 and the enlarged head 9 of the bolt 8 and the resulting movement of the bolt, the latter is withdrawn from the notch 11^a and the arm 7 is moved forward by the spring 21 until the bolt 8 engages in the first notch 11 to the left of the notch 11^a, (Figs. 2 & 3).

Fig. 3 shows the relation of the parts just before the handle 14 reaches the first operative position and with the bolt 8 almost out of engagement with the notch 11^a. The slightest further forward movement of the handle 14 past the position shown in Fig. 3

will release the bolt 8 from the notch 11^a and will allow the arm 7 and shaft 6 to move forward. A movement of the handle still farther in the same direction will operate the bolt in the same manner as before and move it to the next notch in advance. When the handle is moved in the direction opposite to that described above and indicated in Fig. 3, the pins 18 and 20 will act in a manner similar to that described above in connection with the pins 17 and 19. Movement beyond the full "on" position in either direction is prevented by one or more pins 24 projecting upward from the ring 12 in the path of the pin 16.

The projections between the notches are of different heights, depending upon the distance the controller is to move between positions. The projections 22 (Figs. 2 and 3) are shown higher than the projections 23; i. e., the inner surface of the ring at 22 is of smaller radius than at 23. The heights of these projections are so proportioned that the bolt 8 will not leave the notch corresponding to one position until the handle has reached the next position in advance, and the handle cannot be moved beyond said advance position without first releasing the bolt 8 and causing the shaft to move into the position corresponding to the position occupied by the handle. In fact, the shaft is held in a certain position until the handle just reaches the advanced position, independent of the distance apart of said positions, so that for movement between some positions the pins 17 or 18 must move the head 9 and bolt 8 a greater distance than for movement between other positions. Thus there is no danger of the handle being moved so far as to cause the controller to jump several notches at a single movement of the handle.

Obviously, many modifications may be made in the specific structure herein set forth, and I aim to cover in the following claims all such modifications which come within the spirit and scope of my invention.

Having thus described my invention, what I claim as new and desire to secure by Letters Patent is:

1. In combination, a shaft, a notched member, a bolt engaging said notched member to hold the shaft in any desired position, an operating handle, a yielding connection between the shaft and the handle, and means for releasing the bolt from the notched member when the handle has been moved into the desired position in either direction to permit the shaft to rotate under the influence of said yielding means into a position corresponding to the position of said handle.

2. In combination, a controller shaft, an arm fastened thereto and carrying a sliding bolt, an internally notched ring with which said bolt engages, a handle loosely mounted on said shaft, but yieldingly connected therewith, and means for releasing said bolt from the notched ring when the handle reaches the next position in advance to permit the shaft to rotate under the action of said yielding means into said advance position.

3. In combination, a controller shaft, a notched member having notches spaced at irregular distances apart, said notches corresponding to the positions of the controller, a sliding bolt engaging said notched ring to hold the shaft in any desired position, an operating handle, a spring connecting said handle with the shaft, and means for releasing said bolt to permit the shaft to move into said advance positions just as the handle reaches a predetermined advance position independent of the distance apart of the notches corresponding to the controller positions.

4. In a controller, a shaft, an operating handle, a spring connecting said shaft and handle, a sliding bolt engaging notches corresponding to the controller positions to hold the shaft in a certain position until the handle is moved into the next advance position independent of the distance apart of said position, and means for releasing the bolt when the handle reaches the advance position to permit the shaft to move into said advance position under the influence of said spring.

5. In combination, a controller shaft, an operating handle, a spring connecting said shaft and handle, a notched member having the height of the projections between notches proportional to the throw of the shaft between operative positions, a sliding bolt engaging said notched-member to hold the shaft in any desired position, and means for releasing said bolt to permit the shaft to move into said advance position just as the handle reaches an advance operative position.

6. In combination, a handle, controller mechanism having a series of unequally spaced operative positions and biased to move with said handle though movable independently thereof, and a sliding bolt for locking the controller mechanism in any operative position until the handle is moved into the next operative position.

In testimony whereof I affix my signature, in the presence of two witnesses.

ARTHUR J. BROWN.
